UNITED STATES PATENT OFFICE.

FRANK L. BAKER, OF WILMINGTON, DELAWARE, ASSIGNOR, BY MESNE ASSIGNMENTS, TO THE DIAMOND PAPER BAG COMPANY, OF SAME PLACE.

PAPER-BAG MACHINE.

SPECIFICATION forming part of Letters Patent No. 484,281, dated October 11, 1892.

Application filed September 8, 1891. Serial No. 405,070. (No model.)

To all whom it may concern:

Be it known that I, FRANK L. BAKER, a citizen of the United States, residing at Wilmington, in the county of New Castle and State of Delaware, have invented certain new and useful Improvements in Paper-Bag Machines, of which the following is a specification.

My invention relates to the manufacture of paper bags, and more especially to machines of the character shown in Patent No. 415,950, granted November 26, 1889, which are adapted to be used in the manufacture of either flat or square bottom bags having pasted, tucked, and folded bottoms.

It has for its object to improve the construction and arrangement and mode of operation of such machines to enable them more perfectly and satisfactorily to carry out the various operations necessary for making a complete bag.

My invention consists in a certain construction and arrangement of parts of the machine, whereby the folding and pasting of the bag-bottom may be carried out, as will be more specifically pointed out hereinafter, and for which I made application for patent in Canada on the 18th day of November, 1891, Serial No. 58,543.

Referring to the accompanying drawings, in which I have shown the preferred embodiment of my invention, Figure 1 is a longitudinal vertical section of the machine. Fig. 2 is a plan view of the same. Fig. 3 is a detached view of the gripping-rolls and pasting devices. Fig. 4 is an enlarged view of one of the rolls and the tucking-blade. Fig. 5 is a sectional view of the same.

In the accompanying drawings I have illustrated sufficient of a paper-bag machine to clearly disclose my invention, and in which 21 represents the feed-rolls for feeding the tube over the usual former, and 20 a rotary cutting-knife for severing the tube into bag-lengths, operating in connection with the ordinary stationary knife, and 16 and 17 are the folding-rollers for forming the bottom. Between the cutting-blade and the bite of the rollers is a funnel-shaped guide 14, and a folding-blade 12 is mounted in rock-arms 15 and is adapted to be operated substantially as set forth in the patent above referred to.

Mounted on the frame of the machine is a paste-box 4, in which moves a vertically-reciprocating paster 6, it being operated by the rock-arm 2, which in turn is vibrated by the arm 3, taking into the groove of a cam 1, and motion is imparted to this cam through a train of gears, which need not herein be specifically described.

One of my improvements relates to the means of controlling the supply of paste from the paste-box 4 by means of the reciprocating blade 6. This blade is arranged parallel to the front side of the box, the lower portion bearing on a bar 13, being held in contact therewith by a spring 7. Passing through the bottom of the box is a doctor or scraper blade 9, the ends of which are prolonged so as to extend to the front at each side of the paste-blade, and this doctor is normally under the stress of a spring or springs 8, secured to the paste-box, so that it is held in proper position with relation to the vertically-moving paste-blade. In order to regulate the amount of paste delivered by the blade, I provide means for adjusting the doctor, and in the present instance I have shown the screw-rods 5, mounted on the front side of the paste-blade and having conical ends which bear upon the projecting fingers or extensions of the doctor 9, and it will be seen that by adjusting these screw-rods the space between the doctor and the operating-surface of the paste-blade may be nicely and accurately adjusted, so that the precise amount of paste will be delivered by the blade.

Another and important feature of my invention relates to the manner of applying paste to the folded end of the bag-blank, and in carrying out this feature of my invention I provide a movable paste-bar 10, which is arranged above and practically between the rolls 16 and 17 and slides in suitable guides in the frame of the machine, being moved forward by a cam or projection 11 or other equivalent means, and being returned to its normal position by a spring or springs 18. This paste-bar has an inclined top surface, and as the tube is fed past the cutters and over the roll 16 its end strikes this inclined surface of the paste-bar and rides upon it, and when it has reached the proper position the paste-

blade 6 descends and the forward end of the tube is creased and the end bent up against the paste-blade to receive the paste. At the moment the paste-blade reaches its lowermost position, or, if preferred, just before it reaches this position, the paste-bar is forced forward by the cam 11, so as to grasp the end of the tube between its forward surface and the surface of the paste-blade and to press the end of the tube firmly against the blade. The cams are so shaped that these operations will be properly timed, and, preferably, there will be a dwell, the paste-blade being held in its lowermost position and the paste-bar 10 clamping the end of the tube against it for a time sufficient to insure the proper distribution of the paste and attachment and transference to the bag-bottom. This I find to be a very important feature, as the pressure of 15 the bag-bottom against the paste-blade insures an even and smooth distribution of the paste, as well as a complete adherence of the paste to the end of the tube. Moreover, this combined action of the paste-blade and paste-bar 20 performs another important function in that it firmly holds the end of the advancing tube stationary until sufficient of the tube has been fed forward by the feed-rollers to allow the requisite slack to insure a proper 25 severance of the bag-lengths from the tube by the rotating knife and without danger of the bag being distorted or displaced, so that the bottom will not be evenly made. When the 30 bag-length is severed, the folding or tucking blade 12 is brought into operation to tuck the 35 bottom of the bag-length into the bite of the rollers 16 17, and it will be seen that the tucker-blade does not have to crease the blank for the bottom fold, as this is already performed 40 by the paste-blade and paste-bar co-operating therewith, the tucker-blade merely operating to push the bottom into the bite of the rollers. Heretofore this folding or tucker-blade 45 has been made with a straight edge, and it has required a great nicety of adjustment of the parts to prevent the tucker-blade being caught in the bite of the rollers, and thereby 50 impeding the operation, especially when the machine is driven at a high rate of speed. In order to avoid this danger, I provide the tucker-blade 12 with cut-away portions, so as to leave the projections 25 (best shown in Fig. 4) on its tucking-edge, and these 55 projections may be of sufficient number to properly insert the bag-bottom into the bite of the rollers without danger of tearing the paper, and as the crease has already been formed by the folding-blade I find that the tucker-blade made as described performs its functions 60 thoroughly and satisfactorily. As a further safeguard to prevent any accidental sticking of the tucker-blade between the rollers, I cut away a portion of the rollers, either or both, at points corresponding with the projections 65 25. Thus in Figs. 4 and 5 I have shown the roller 16 as having cut-away or recessed portions 24, corresponding with the projection

25 on the tucker-blade, and thereby I prevent any possibility of the tucker-blade sticking or being caught in the bite of the rolls. 70

Such being the construction and arrangement of the devices, their operation will be fully understood and need not be set forth in detail further than to say that the movements of the different parts of the machine are so timed that the paste-blades preferably move downward at the same speed the tube is fed over the roll 16 by the feed-rolls, and the end of the tube is held between the paste-blade and paste-bar a time sufficient to allow the 80 severance of the bag-blank from the paper tube. As soon as the paste-blade moves upward the tucker-blade operates to tuck the end of the bag-blank into the bite of the rollers. 85

While I have described the paste-blade as reciprocating in a vertical line and the paste-bar moving against the blade, it is evident that I can make the paste-bar stationary and the blade move against its forward face and accomplish the same results in substantially 90 the same manner. Other variations in the details of construction and operation of devices will readily suggest themselves to those skilled in the art, as it is evident that the details of construction and arrangement set forth may be varied without departing from the general principles of my invention. The features of invention may be adapted to various styles and forms of machines other than that indicated in the drawings and the method 95 or steps of my process of forming the bottoms of paper bags be fully carried out. 100

What I claim is—

1. In a paper-bag machine, the combination of a paste-applier, and a presser whereby the 105 end of the bag is creased, supplied with distributed paste and held during the slackening and severing of the blank from the web, with means for completing the fold of the creased and pasted end portion, substantially as described. 110

2. The combination, with the paste-blade carrying paste on one of its sides, of a paste-bar between which and the paste-blade the paper is grasped, substantially as described. 115

3. The combination, with the paste-blade carrying paste on one side, of the paste-bar between which bar and blade the paper is grasped, one of the parts being movable with respect to the other, substantially as described. 120

4. The combination, with the reciprocating paste-blade carrying paste on one of its sides, of the movable bar adapted to press the paper against the paste-blade, substantially as described. 125

5. The combination, with the feed-rolls, the guide, and cutting-blades, of a paste-bar having an inclined surface and a reciprocating paste-blade, the arrangement being such that the 130 paper is fed over the inclined surface of the bar and is pressed against the face of the paste-blade, substantially as described.

6. The combination, with the feed-rolls,

guide, and cutters, of the paste-bar, a reciprocating paste-blade, and an operative mechanism for said bar and blades, the arrangement being such that the paper is grasped between the bar and blade and held while the bag-length is being severed, substantially as described.

5 7. The combination, with the rolls, of a reciprocating paste-blade, a paste-bar co-operating with the paste-blade to grasp and crease the end of the tube and apply paste thereto, and a tucker for tucking the creased portion into the bite of the roller, substantially as described.

10 8. The combination, with the rolls having recesses 24, of a tucking-blade having projections corresponding with said recesses, substantially as described.

15 9. The combination, with the pasting and creasing device, of a tucking-blade having projections and the rolls having recesses 24 corresponding with the projections to form a clearance for said projections, substantially as described.

10 10. The combination, with the paste-box 25 and vertically-reciprocating paste-blade, of a doctor-plate for the blade and adjusting screw-rods having conical ends, substantially as described.

15 In testimony whereof I have signed my name to this specification in the presence of two subscribing witnesses.

FRANK L. BAKER.
